US00D375450S

United States Patent [19]

Bidwell et al.

[11] Patent Number: Des. 375,450

[45] Date of Patent: **Nov. 12, 1996

[54] **ULTRASOUND TRANSDUCER PROBE HOLDER WITH GROOVE**

[75] Inventors: **Dean J. Bidwell; Stephen B. Hooper**, both of Redmond, Wash.

[73] Assignee: **Siemens Medical Systems Inc.**, Iselin, N.J.

[**] Term: **14 Years**

[21] Appl. No.: **44,687**

[22] Filed: **Sep. 29, 1995**

[52] U.S. Cl. **D8/356**

[58] Field of Search **D8/354, 356; D24/127, D24/128; 174/153 G; 248/56**

[57] **CLAIM**

The ornamental design for the ultrasound transducer probe holder with groove, as shown.

DESCRIPTION

FIG. 1 is a perspective view of an ultrasound transducer probe holder with groove embodiment of this invention; FIG. 2 is a side view of the ultrasound transducer probe holder groove of FIG. 1;

FIG. 3 is another side view of the ultrasound transducer probe holder groove of FIG. 1;

FIG. 4 is another side view of the ultrasound transducer probe holder groove of FIG. 1;

FIG. 5 is another side view of the ultrasound transducer probe holder with groove of FIG. 1;

FIG. 6 is a top side view of the ultrasound transducer probe holder with groove of FIG. 1; and,

FIG. 7 is a bottom view of the ultrasound transducer probe holder with groove of FIG. 1.
